UNITED STATES PATENT OFFICE

ALFRED R. WRIGHT, OF ESSEX, CONNECTICUT

CARD TABLE

Application filed July 2, 1929. Serial No. 375,350.

This invention relates to the construction of card tables of the folding leg class which are particularly adapted for bridge playing.

The object of the invention is to provide a light table which is so shaped that it will be very convenient for the players, in that while the area is ample to accommodate the cards of a bridge game, the distance from a player to the opposite side is relatively short in order that the dummy hand may be easily reached, and the corners used for the handy placement of counters, candy, cigars, cigarettes, or glasses of beverage in localities that will not obstruct or interfere with the surface of the table necessary to be utilized for playing.

This object is attained by inwardly recessing or concaving the sides of the table top so that the players may sit forward, and leaving projecting corners of considerable width for holding the accessories. The legs are attached to the under side at the corners in such manner that when opened they will be suitably braced in all directions and will afford a wide, firm base for the table, and that when folded up against the under side of the top will extend across the cavities and afford handles by means of which the table may be carried about, clips being provided for retaining the legs closed and also from collapsing when opened. It is preferred to cover the playing area of the top of the table with a soft fabric, and to have the extended corners of hard polished material and can be readily cleaned of any stains or débris resulting from the spilling or dropping of the refreshments.

In the accompanying drawings Fig. 1 shows a plan of the table with the legs folded. Fig. 2 shows a side elevation with the legs opened and broken off. Fig. 3 shows a portion of the under side of the table with the legs folded. Fig. 4 is a view on larger scale showing details of the leg attachment means. Fig. 5 is a detail showing the means for locking the legs open.

The body of the table top 1 may be made of any suitable material, as wood or paper-board, and its edges are recessed to form concavities 2 on all four sides. The recesses are made in such manner as to leave wide ex-

tensions 3 at the four corners of the table. With this shape the players may sit close to the playing area 4 of the top, while the corners will project more or less on each side of and between the players. The upper surface of the table top may be finished in any desired manner, preferably by covering the playing surface with a soft fabric of suitable color, as indicated at 5, and covering the corners with a material that may be polished, for example, celluloid, bakelite or metal, as indicated at 6.

The legs 7 are hinged by pins 8 to brackets 9 fastened to the under side of the table at the corners in such positions that the legs when folded against the under side of the top will extend from corner to corner across the cavities in the edges of the table as illustrated in Figs. 1 and 3. Strips 10 may be fastened to the legs and hinged on the pins 8 so as to turn with the legs and brace them in one direction when they are open. Clips 11 may be attached to the under side of the table in position to clasp the free ends of the legs and retain them folded.

Collapsible braces comprising tubes 12 hinged to the table, and telescoping rods 13 hinged to the legs, are provided for bracing the legs in the other direction when open. A latch composed of a leaf spring 14 fastened to the tube and a pin 15 on the spring adapted to engage a notch 16 in the rod is provided for retaining the collapsible braces in proper relation when the legs are open.

The invention claimed is:

1. A table comprising a unitary top with a plane upper playing surface, said top having four concaved side edges and four wide radial and integral extensions separating the concaved sections, with legs hinged to the under side of said extensions and adapted to fold against and open from the table, said legs when folded extending across the concaved recesses in the side edges and providing handles for transporting the table.

2. A table comprising a unitary top with a plane upper playing surface, said top having four concaved side edges and four wide integral extensions in the same plane and separating the concaved sections, with legs hinged

to the under side of said extensions and adapted to fold against the table and extend across the concaved openings, the playing surface of the table being covered with fabric, and the said extensions covered with hard, easily polished material.

ALFRED R. WRIGHT.
